UNITED STATES PATENT OFFICE.

ALFRED I. CONE, OF NEW YORK, N. Y.

SPRING-OPERATED SELF-CLOSING SHAKER RECEPTACLE.

Application filed May 6, 1926. Serial No. 107,021.

One of the objects of the present invention is to provide a convenient means for operating the spring so that the self-closing package may be opened for the purpose of discharging its contents by pressure, say, of the thumb or a finger of the hand with which the receptacle is being held.

Another object of the invention is to reduce to a minimum the chances of opening the package for the discharge of its contents by any other than intentional and well-directed digital pressure, and thus to prevent accidents to infants and children, for instance.

15 A further object is to provide improved spring-operating means and to simplify the labor of assembling the parts in putting up.

Other objects, advantages, and features of the present invention are inherent in the 20 novel construction, arrangement, and combinations of the parts, as will be better understood from the following more detailed description and the accompanying drawings and claim.

25 In the accompanying drawings, forming a part of this specification, and in which like numerals are employed to designate like parts throughout the same.

Figure 1 shows a side elevational view illustrating the side and top walls and the 30 position of the operating means in the side wall of the receptacle;

Figure 2 presents an inside plan view of the top wall or cover 4 of the receptacle and 35 of the sliding disk 6 positioned within the cover and in contact with the top wall thereof, both of which are perforated in such a manner that the perforations therein may be caused to register by pressure upon 40 the operating push-button 3 and the spring 9.

Figure 3 shows a vertical cross-section of the container along the lines III—III of Figure 1;

45 Figure 4 is a detail drawing of a preferred form of operating spring 9 which is provided with lugs 7 and 8, the specific function of which will be explained hereafter, and having affixed thereto the perforated sliding disk 6, which is shown in position in Figures 2 and 3 as positioned with reference to the inner aspect of the top wall 4 and the perforations therein. (Dotted lines indicate changed positions of the disk 50 and the spring under pressure upon the push-button 3.)

The spring-actuating means, as illustrated, 60 consists of a cylindrical button or rod 3 which is slidably positioned within a sleeve 2 which projects inwardly from the downwardly projecting flange or side wall 4' of the cover. This sleeve 2 opens through an opening in the said wall and is somewhat contracted at its outer end where it is joined to the side wall or downward flange 4' of the 65 cover, so as to limit the outward movement of the outer end of the operating button 3 caused by the pressure of the operating spring after digital pressure upon the button has been released.

The inner end of the button is provided 70 with an opening adapted to hold in engagement the holding lug 8 when the spring 9 is positioned, as shown in Figures 2 and 4, to prevent sideward and downward movement 75 of that end of the spring, and to hold the slideable perforated disk 6 in close contact with the inner surface of the perforated top wall of the cover 4. The end of the operating spring which is thus engaged with 80 the inner open end of the button 3 is also provided with a guide lug 7 adapted to loosely engage the opposite free end 10 of the spring 9 when the same is bent over on itself for positioning within the downwardly 85 projecting flange or side wall 4' of the cover to prevent a downward movement of the said free end 10 of the spring and to retain it in effective operative position.

The operating spring 9 is positioned within 90 the cover as shown in Figures 2 and 3. The dotted lines in Figure 2 indicate approximately the line of movement of the perforated sliding disk and the spring in the special form of adaptation of the invention herein illustrated. The spring 9, shown in the drawings as a broad band-spring, is a preferred form, as the width of the spring here tends also to frictionally hold the spring 9 in position as shown in 95 Figure 3.

In assembling the parts the slideable button or rod 3 is placed within the sleeve 2, as illustrated in Figure 3, the holding lug 8 is set within an opening at the inner end 105 of the button 3, the end 10 of the spring 9 is forced into position between the inner side of the sliding disk 6, and the guide lug 7 for a sufficient distance to enable the bent spring to fit into the space on the inside of 110 the cover between the inner ends of the sleeve and button, 2 and 3, and the opposite

side of the side wall 4' of the cover. The button 3 is preferably hollow as shown in Figure 3.

The perforations 5 in the top wall of the cover and 5' in slideable disk member 6, attached to the spring 9, are so disposed as to cause them to register when appropriate pressure is applied to the operating button 3 and to slide out of alignment when such pressure is released through the reaction of the spring.

The perforated top wall or cover is mounted upon the container by inserting the side wall 4' of the cover 4 within the side wall of the container body 1, so that the sleeve 2 and the button 3 will be in the relative positions indicated by the opening 1' in the side wall of the body, as shown in Figures 1 and 3.

The top wall or cover may optionally be inserted into the container body to be held in position frictionally, or it may be soldered or clamped to the body or otherwise permanently fastened thereto by any suitable means without departing from the scope and spirit of the invention.

The U-shaped opening at or near the upper edge of the side wall of the receptacle, as shown in the drawing in Figure 1, for engaging the outer end of the sleeve 2 and for exposing the button 3, may also be optionally modified to form a circular or other form of opening of the size and contour of the outwardly projecting margin of the sleeve 2 and positioned slightly below the top edge of the receptacle body at a sufficient distance from the said top edge so that the said slightly protruding margin of the outer end of the sleeve may be caused to snap into position and held thereby the said opening after it has once been forced into that position.

The spring member and the precise form and the manner of attachment of the sliding disk are also susceptible of considerable modification from the particular form illustrated and described. Preferably, the perforated sliding disk is made integral with

the spring member, for instance as shown in Figure 4, and of the same material, and tilted slightly upward at the free edge thereof and away from the course of the spring proper, so as to assure continued close contact with the top wall of the cover by the upward pressure caused when the lug 8 is forced into position into the open end of the push-button or rod resting within the sleeve.

It is to be understood that the forms of this invention herewith shown and described for the purposes of illustration are to be regarded as a preferred adaptation of the same, and not as a limitation thereof, as it is obvious that various changes may be made in the shape, size, character, and arrangement of the parts without departing from the spirit of the invention or the scope of the subjoined claim.

Having thus described my invention, what I claim as new and desire to secure by Letters Patent is:

A spring-operated self-closing shaker receptacle having for its operating means a hollow push-button in the side wall slidably retained within a sleeve extending inwardly of the container body, the interior open end of said push-button being in contact with a horizontal actuating loop spring having as an integral part thereof a slideable perforated closure plate lying in close surface contact with the inner aspect of the perforated top wall; the said spring being provided at one end with an outwardly projecting holding and supporting lug for engaging the spring within the hollow of the said push-button in operative position and for resting upon the lower inside of the hollow button in such a manner as to support the said closure plate and to prevent downward movement of the same from its position of slideable contact with the top wall, and provided also at the same end with an inwardly projecting guide lug for receiving and holding the other slideable end of the said spring in operative position.

ALFRED I. CONE.
